UNITED STATES PATENT OFFICE.

HARRY A. MILLER, OF PASADENA, CALIFORNIA, AND BENJAMIN G. GILBOUGH, OF CHICAGO,
ILLINOIS.

SPARKING DEVICE.

No. 872,629.

Specification of Letters Patent.

Patented Dec. 3, 1907.

Application filed February 14, 1906. Serial No. 301,104.

To all whom it may concern:

Be it known that we, HARRY A. MILLER and BENJAMIN G. GILBOUGH, citizens of the United States, residing, respectively, at Pasadena and Chicago, in the counties of Los Angeles and Cook and States of California and Illinois, have invented a new and useful Improvement in Sparking Devices, of which the following is a specification.

10 Our invention relates particularly to sparking devices for explosive engines, having the general character of the sparking device disclosed in Letters Patent No. 805,790 granted to B. G. Gilbough, November 28th, 15 1905.

Our primary object is to provide a practical form of sparking device of the general character indicated, in which, however, the vibratory electrode employed is mounted 20 upon and carried by the gas-actuated spring-retracted piston employed in connection with the device.

The invention is illustrated in the accompanying drawing, in which—

25 Figure 1 represents a sectional view of our improved sparking device applied to an engine-cylinder, the cylinder being shown brokenly; Fig. 2, a sectional view of said device in a modified form; and Fig. 3, a plan view of a spider or spring-holder, forming a part of the construction shown in Fig. 2.

In the construction shown in Fig. 1, A represents an engine-cylinder; and B our improved sparking device applied thereto.

30 The device B comprises a tubular plug b, having screw connection with the engine-cylinder; a cylinder b¹ insulatingly mounted on the plug b and secured thereto by a nut b²; a piston b³ movable in the cylinder b¹; a vibratory electrode b⁴ having ball joint connection with the inner end of the piston; an end cap b⁵ for the cylinder b¹; a spring b⁶ which serves both in retracting the piston and moving the vibratory electrode upon its 35 pivot; and a binding post b⁷ connected by a screw b⁸ to the end cap b⁵, the member b⁷ being spring-held by means of a spring b⁹ and the screw b⁸ serving also in the adjustment of the tension of the spring b⁶. As shown, the 40 cylinder b¹ opens at its inner end into the interior of the tubular plug b. The piston b³ is tubular in form, and has an inner end b¹⁰ through which the vibratory electrode b⁴ extends, the member b¹⁰ being provided on its 45 lower surface with a half-socket for a ball b¹¹,

constituting the pivot or trunnion of the member b⁴. The ball is held in place by means of a removable socket-section b¹² applied beneath the bottom portion b¹⁰ of the piston and having a complementary half-spherical recess for the ball. The upper end of the member b⁴ is equipped with a head comprising a short arm b¹³ adapted to contact with one side of the interior of the cylinder, as shown in Fig. 1, and a cam arm b¹⁴ having an inclined surface b¹⁵ adapted to engage an inclined cam surface b¹⁶, formed on the interior of the cylinder b¹, the surface b¹⁶ forming the bottom wall of an annular recess b¹⁷ within the outer end portion of the cylinder. The upper portion of the vibratory electrode is provided with a guide-slot b¹⁸, which moves on a transverse guide-pin b¹⁹ extending across the bore of the piston. The spring b⁶ is a coil-spring whose ends are equipped with studs b²⁰, having spherical heads which fit in half-spherical recesses provided on the head of the vibratory electrode and at the lower end of the screw b⁸.

Normally, the piston b³ occupies a position 80 at the inner end of its stroke, as shown in Fig. 1, and the vibratory electrode occupies the position shown with the arm b¹³ bearing against the inner wall of the tubular piston and the inner end of the electrode out of contact with a stationary electrode b²¹ at the inner end of the tubular plug b. When the piston moves outwardly, under the pressure of the compressed gas within the engine-cylinder, the vibratory electrode, still occupying the position shown in Fig. 1, moves with the piston until the lower end of the vibratory electrode encounters the stationary electrode b²¹, when further movement of the piston causes the electrode b⁴ to turn upon 90 its pivot until the center of the upper end of the vibratory electrode passes the central axis of the piston, when the spring b⁶ operates to force the upper end of the vibratory electrode as far to the right as possible, as 100 viewed in Fig. 1, thereby breaking the contact between the electrodes. In this operation, the arm b¹⁴ enters the recess b¹⁷. In the return movement of the piston, after the gas pressure upon it has been relieved, the 105 surface b¹⁵ of the arm b¹⁴ encounters the surface b¹⁶ on the interior of the cylinder, thereby throwing the upper end of the lever b⁴ to the left until it passes the longitudinal central axis of the cylinder, whereupon the spring 110

*b*⁶ operates to throw the vibratory electrode to the position shown in Fig. 1.

A battery C is connected by conductors *e* with the outer end of the sparking device and with the engine - cylinder, it being understood that the engine-cylinder is in electrical connection with the tubular plug *b*. It is obvious that the current will pass when the electrodes are closed and will be interrupted when the electrodes are separated thereby producing a spark. The ball-joint connection between the vibratory electrode and the piston is gas-tight, or practically so, obviating the danger of excessive heating of the 10 sparking device and obviating loss of pressure from the engine-cylinder.

In the modification shown in Fig. 2, A represents an engine - cylinder; and D a sparking device applied thereto. In this 20 form, the sparking device comprises a tubular plug *d*, having screw connection with the engine-cylinder; a cylinder *d*¹ insulatingly carried by the plug *d*; a nut *d*² securing the cylinder to the tubular plug; a piston *d*³ within the cylinder *d*¹; a vibratory electrode *d*⁴ mounted to be carried with the piston; an end cap *d*⁵ for the cylinder; a piston spring *d*⁶ encircling the cylinder *d*¹, and having its inner end mounted on a spider 30 *d*⁷, whose upper end is equipped with arms *d*⁸, which project through slots *d*⁹ with which the cylinder is provided, the inner ends of said arms bearing upon an external flange *d*¹⁰ with which the piston is equipped at its 35 upper end; a nut *d*¹¹ having threaded connection with the exterior of the upper portion of the cylinder and serving to adjust the tension of the piston-spring *d*⁶; and a spring *d*¹² confined between the upper portion of the vibratory electrode and the inner wall of the piston *d*³ and serving normally to hold the vibratory electrode as shown in full lines in Fig. 2. The tubular plug *d* carries a stationary electrode *d*¹³ having a sloping surface adapted 45 to engage a sloping surface *d*¹⁴ on the inner end of the vibratory electrode.

The piston *d*³ is of tubular form, having an inner end *d*¹⁵ through which the vibratory electrode extends, said member *d*¹⁵ being provided on its lower surface with a socket-portion for receiving a ball *d*¹⁶, forming the trunnion or pivot of the vibratory electrode. The complementary portion of the socket is provided in a removable socket-section *d*¹⁷ applied at the inner end of the piston. The joint is such as to afford a gas-tight connection between the piston and the vibratory electrode. A binding post *d*¹⁸ is connected with the member *d*⁵, and the member *d*⁵ is provided at its inner side with a recess *d*¹⁹, having at its upper portion a conical wall *d*²⁰, adapted to engage the outer end of the vibratory electrode. When the piston *d*³ moves outwardly under the pressure of the compressed gas within the engine-cylinder, it car-

ries with it the vibratory electrode whose inner end is quickly brought into contact with the stationary electrode, causing the electrode to vibrate to about the position indicated by dotted lines in Fig. 2, which brings the upper end of the vibratory electrode into position to engage the conical surface *d*²⁰ of the end-cap *d*⁵, further movement of the piston causing a completion of the vibratory movement in one direction and a break between the electrodes, the breach being further widened by the movement of the surface *d*¹⁴ above the apex of the stationary electrode.

While the construction shown in Fig. 2 is somewhat more complex than the construction shown in Fig. 1, this construction, nevertheless, has an advantage in the external arrangement of the piston-spring, providing for circulation of the air. A battery E is connected by conductors *e* with the binding post of the device and with the engine-cylinder, it being understood that the engine-cylinder is in electrical connection with the tubular plug *b*. It is evident, therefore, that the circuit will be closed when the electrodes are closed, and that an interruption of the current will occur when the electrodes are separated, producing a spark.

What I regard as new and desire to secure by Letters Patent, is:

1. An ignition device comprising a cylinder having its inner end adapted for communication with an engine cylinder and equipped with a fixed electrode, a gas-actuated piston, and a vibratory electrode disposed longitudinally of said cylinder and mounted upon and carried by the piston, for the purpose set forth.

2. An ignition device comprising a cylinder having its inner end adapted for communication with an engine cylinder, a gas-actuated piston, and a vibratory electrode disposed longitudinally of said cylinder and mounted upon and carried by the piston and having a gas-tight joint therewith, for the purpose set forth.

3. An ignition device comprising a cylinder having its inner end adapted for communication with an engine cylinder, a gas-actuated piston of tubular form having an inner end provided with a socket-section, a vibratory electrode having an enlarged pivotal portion received by said socket-section, said electrode extending through the end of the piston, and a removable socket-section maintaining the pivotal portion of the vibratory electrode in position.

4. An ignition device comprising a tubular plug adapted for connection with an engine-cylinder and equipped with a stationary electrode, a cylinder insulatingly mounted on said tubular plug and having its inner end in communication with the tubular plug, a piston movable in the cylinder of the device,

- a vibrating electrode extending through the piston and having a gas-tight joint therewith, and yielding means for maintaining the piston normally at the inner end of its stroke, 5 and the vibratory electrode normally out of contact with the stationary electrode and in position to be engaged by the stationary electrode upon the initial movement of the piston under the action of gas pressure.
- 10 5. An ignition device comprising a tubular plug adapted for connection with an engine-cylinder, a cylinder insulatingly mounted thereon and in communication with said plug, a piston movable in said cylinder, a vibratory electrode having gas-tight connection with said piston, and a coil-spring normally occupying an oblique position, serving to maintain the vibratory electrode in an oblique position, for the purpose set forth.
- 15 6. An ignition device of the character described, comprising a tubular plug adapted for connection with an engine-cylinder, a cyl-
- inder insulatingly mounted on said tubular plug and in communication with the interior thereof, a tubular piston movable in said second-named cylinder, and having an inner end with a removable section applied thereto and affording a socket for a ball, a vibratory electrode equipped with a ball within said socket, an oblique spring tending to maintain said electrode in an oblique position, a cam-arm carried by the upper end of said electrode, and a cam in the upper portion of the cylinder of the device adapted to engage said cam-arm during the retraction of the 35 piston, for the purpose set forth.
